(57) **CLAIM**

The ornamental design for a mouse, as shown and described.

DESCRIPTION

FIG. 1 is a top, side perspective view of a mouse showing our new design;

FIG. 2 is bottom, side perspective view thereof;
FIG. 3 is a front view thereof, the rear view being identical thereto;

FIG. 4 is a side view thereof, the opposite side view being identical thereto;

FIG. 5 is a top view thereof; and,

FIG. 6 is a bottom view thereof.

The broken lines illustrate portions of the mouse and form no part of the claimed design. The light gray shade lines on the surface portions indicate contour and not surface decoration.
